UNITED STATES PATENT OFFICE.

CHARLES METCALF, OF STREATOR, ILLINOIS.

FLUSHING APPARATUS.

1,333,269.

Specification of Letters Patent.

Patented Mar. 9, 1920.

Application filed June 22, 1915. Serial No. 35,623.

To all whom it may concern:

Be it known that I, CHARLES METCALF, a citizen of the United States, residing at Streator, in the county of La Salle and State 5 of Illinois, have invented new and useful Improvements in Flushing Apparatus, of which the following is a specification.

This invention relates to improvements in flushing apparatus for water closets, water 10 systems, and other supply tanks, and particularly to flushing apparatus of the siphon type.

The object of the invention is to provide a simple, reliable and efficient type of apparatus of this character, which dispenses with the use of packing, which is substantially proof against leakage, or wastage, which secures a perfect connection of the parts without the use of ground joints or expensive 15 fittings, and which will operate with certainty on each flushing action to discharge the water from the tank down to a point within a certain distance from the bottom thereof.

20 The invention consists of the features of construction, combination and arrangement of parts herein fully described and claimed, reference being had to the accompanying drawings in which:—

25 Fig. 1 is a sectional view through a water supply tank, showing the siphon valve mechanism in elevation.

Fig. 2 is a vertical sectional view through the tank and valve mechanism and showing 30 the valve mechanism in its normal position.

Fig. 3 is a view similar to Fig. 2 showing the valve mechanism adjusted for the siphonic action.

Fig. 4 is a sectional plan view on the line 40 4—4 of Fig. 2.

Fig. 5 is a vertical section on an enlarged scale, through the plunger cylinder, showing in dotted and full lines the valves in open and closed positions, respectively.

45 Referring to the drawings, 1 designates a water supply tank or system, within which is arranged a cylinder 2. This cylinder is vertically disposed and has a lower open end 3 elevated a short distance above the bottom 4 of the tank 1. The cylinder 2, as clearly shown in Figs. 2 and 3, is provided with an upper end or wall 4' which is located an appreciable distance below the upper edge or rim of the cylinder proper, said wall 4' being provided with an outlet opening 5 for connection with the short or intake leg 6 of

a siphon tube 7, the longer or discharge leg 8 of which communicates at its lower end with a discharge or overflow pipe 9.

The siphon so suitably connected to and supported within the tank 1, and as shown in the present instance is provided upon its long or discharge leg 8 with a bushing 10 having a collar 11 to bear against the upper surface of the bottom 4 of the tank, said 60 bushing being exteriorly threaded at its lower end to receive a clamping nut 12 engaging the lower side of the tank bottom 4, whereby the siphon tube is clamped in position. The pipe 9 telescopically receives the 65 end of the leg 8 and is connected with the bushing 10 by a threaded coupling member 13. Any other mode of connecting the discharge or overflow pipe 9 with the siphon tube may, however, be employed. 75

Arranged to operate within the cylinder 2 is a vertically movable plunger 14. This plunger comprises a disk or head provided on opposite sides of its center with a pair of waterflow ports or passages 15 controlled 80 by pivoted segmental shaped valves 16, each having a depending projection 17, operating as a weight to normally hold the valves closed. As clearly appears in Fig. 5 from the dotted lines indicating the open position 85 of the valves 16, each of said depending projections 17 has an extension at its lower end adapted to engage the underside of the plunger 14 to limit the upward swing of said valves when the latter are opened and thereby prevent possibility of the valves 16 being swung to such a position that they would not close under the action of gravity. 90

Connected at its lower end with the plunger disk is a stem 18 having its upper end 95 extending through and slidably within a guide tube 19 threaded into the top wall 4' of the cylinder, said stem terminating in an eye 20 for pivotal connection with a controlling lever 21 adapted to be operated by 100 means of a pull chain 22 or other suitable actuating means. The plunger when drawn upward through the action of the lever 21 raises the body of water above it in the cylinder sufficiently to force the water over the 105 top of the bend or arch in the siphon tube, thus starting a siphonic action in the well known way for the discharge of the water from the tank through the siphon tube and pipe 9. In this operation it will, of course, 110 be understood that as soon as the siphonic action starts, the valves 16 will be opened by

the preponderating pressure of the water below them, so as to permit the water to flow freely through the ports 15 from the tank to the siphon tube through the plunger cylinder.

- Arranged about the lower portion of the plunger stem 18 is a coiled spring 24. This spring is made of a predetermined degree of stiffness and of such length as to contact 10 at its upper end with the top wall 41 of the plunger cylinder and be compressed to a certain extent to limit the upward movement of the plunger and to cushion such plunger on the movement. This spring prevents 15 any objectionable violent action of the plunger on its upward motion and also serves the important function of preventing the plunger from rising to an undesirable height, where the pressure of the water 20 from below would not be sufficient to force the valves open, and hence where there would be a tendency of the valves to only partially open, thus restricting the outflow of water and decreasing the efficiency and 25 celerity of the flushing action. The bushing 10 so provided with a passage 24 with which communicates the lower end of a small tube 25, said tube being connected in the usual manner with the tank supply pipe 30 (not shown) and thereby adapted to serve as a refilling tube by which the pool of water in the bowl below is replenished after each siphonic action, as will be readily understood.
- 35 By locating the upper wall 4' of the cylinder below the top edge of the latter, as shown in the drawings and previously described, a small reservoir or chamber for water is thereby provided which will, of 40 course, be filled each time the water in the tank rises to the level of the line $\alpha-\alpha$. Consequently, when the plunger is lifted to start the siphonic action, this water which is retained in said chamber or reservoir will 45 seal the opening in the bushing 19 through which the rod 18 extends and may gradually drip through said opening. The capacity of the reservoir or chamber at the top of the cylinder for this water is so designed 50 that the opening through which the rod 18 passes will be covered during the entire siphonic action and thereby prevent the possibility of a break in the siphon which might otherwise occur by a leakage of air 55 through said opening. By this arrangement, I avoid the necessity of an air tight fit or the use of packing glands where the rod 18 passes through the top wall of the

cylinder, thus minimizing the expense and at the same time providing an efficient and 60 effective arrangement. As will be understood, water will remain in said reservoir at the top of the cylinder after the level of the water in the tank has dropped below the top 65 edge of the cylinder during the siphonic action.

I claim:

1. A siphon flushing apparatus comprising a water supply tank, a siphon tube having its discharge leg extending through the bottom of the tank, a plunger cylinder having an open lower end arranged in proximity to the bottom of the tank and communicating at its upper end with the intake leg of the siphon, a plunger operating in said cylinder and provided with segmental ports at diametrically opposite points therein and having pivotally mounted, upwardly opening check valves controlling said ports, contact members carried by the valves and projecting through the ports below the plunger, said contact members being arranged to engage the main part of the plunger to limit the upward movement of the valves before the latter reach a vertical position, a stem connected with the plunger, operating means connected with the plunger stem, and a cushioning spring upon the stem normally seated at its lower end against the plunger and operative to engage the top wall 90 of the cylinder when the plunger is lifted to arrest and cushion the upward movement of the plunger.

2. A siphon flushing apparatus comprising a water supply tank, a siphon tube having its discharge leg extending through the bottom of the tank, a collar upon said leg extending through the bottom of the tank and having an enlarged upper end, said enlarged upper end being provided with a lateral passage communicating with the interior of said leg, a refill tube in communication with said passage, an outlet pipe telescoped with respect to said discharge leg of the siphon tube, and means on the under 100 side of the bottom of the tank coöperable with said collar for securing the latter and the outlet pipe in position with respect to the tank.

In testimony whereof I affix my signature 110 in presence of two witnesses.

CHARLES METCALF.
